VACUUM TUBE AND METHOD OF
MAKING SAMEArchie J. McMaster, Highland Park, Ill., assignor
to G-M Laboratories, Inc., Chicago, Ill., a corporation of Illinois

Application May 14, 1932, Serial No. 611,255

4 Claims. (Cl. 49—78)

My invention relates in general to bulb construction and method for making the same, and more particularly to the method of attaching an exhaust tube to such bulbs.

5 In the manufacture of electric lamp bulbs, radio tubes, and the like, from which it is necessary to exhaust the air, various methods have been used to attach an exhaust tube for connecting the bulb to a vacuum pump. For many 10 years it has been desirable to connect the exhaust tube to a part of the bulb such that the exhaust tube tip when it is sealed off from the pump, can be readily covered by a base or fitting through which connecting wires are also brought 15 out. Such construction reduces the fragility of the bulb because the tip of the exhaust tube is not exposed to the hazard of breakage after the base is attached.

An object of this invention is to provide a bulb 20 having an exhaust tube sealed to the stem of the bulb.

A further object is to provide a type of bulb construction which will be economical to manufacture.

25 A further object is to provide a method of manufacturing such bulbs in which the production shrinkage due to imperfect results will be reduced to a minimum.

A further object is to provide a bulb construction which will be stronger and less fragile during 30 subsequent operations in the manufacture of the completed article before the base is attached.

Other objects and advantages will appear as the description proceeds.

35 For a better understanding of this invention reference is made to the accompanying drawing, wherein,

Fig. 1 shows a completed bulb made in accordance with my invention.

40 Fig. 2 is a view of the component parts of the stem of such a bulb mounted on a wire die block of a stem making machine.

Fig. 3 is a sectional view of the stem of such a bulb.

45 Fig. 4 is a sectional view of the press of a stem of such a bulb, taken on the line 4—4 of Fig. 3.

Fig. 5 shows a modification of my invention in which the press is made in the bulb without the use of a separate stem tube.

50 Fig. 6 is a view of the component parts of such a bulb mounted on a wire die block of a stem making machine.

In 1894, Burnette and Doane disclosed in United States Letters Patent No. 516,800 a 55 method of bulb construction in which an exhaust tube such as 13 in Fig. 1 was sealed to the stem 12 of a bulb 11 in a manner which permitted the protection of the exhaust tube tip after sealing from the pump by means of a base as is common in electric lamp bulbs in use today. Their

method of attaching the exhaust tube 13 to the stem tube 12, involved placing in the stem tube 12, the exhaust tube 13 containing a refractory material. The stem tube 12 was then sealed and pressed on to the exhaust tube 13 forming the 5 press as at 14. The refractory material served to maintain the opening through the press during the sealing and pressing operation, the refractory material later being removed from the opening. The refractory materials suggested in 10 their specification were carbon, iron, asbestos pastes, etc.

For years since the patent to Burnette and Doane attempts have been made to apply this technique on a production basis. To my 15 knowledge these attempts have been largely unsuccessful due primarily to the difficulty in removing the refractory material from the opening after the press has been made. Also when it has been possible to accomplish this result, the 20 stem has been fragile at the joint 20 between the exhaust tube 13 and the press 14.

Various other methods have been suggested for maintaining the opening 16 in press 14. In making a thorough study of this matter I have found 25 that each suggested method has been subject to severe defects if it is desired to produce bulbs on a production basis. In making my tests, I have devised a stem testing machine with which it is possible to accurately test the resistance 30 against breakage of the exhaust tube from the stem tube at the joint 20.

In practicing my invention I rigidly place a plug 24 of wire or rod in wire die block 27 as in Fig. 2. The wire die block, 27, is similar to that used in ordinary stem making machines and is well known to those skilled in this art. I have found that it is very desirable to slightly taper the portion 26 of plug 24 which extends from wire die block 27. Stem tube 12 and exhaust tube 13 are supported by suitable means above wire die block 27 as is common practice. Wires 17 and 117 are inserted in the wire die block. Extensions of wires 17 and 117 are welded inserts 19 and 119 of suitable properties to properly seal 45 to the glass when the press is formed. The lead wires 21 and 121 welded to inserts 19 and 119 provide connection to external apparatus when the bulb is completed.

In the process of manufacturing the stem, the 50 sequence of operations is as follows. The tapered portion 26 of plug 24 is first coated with a film 28 of finely divided material such as lamp black, gas carbon, graphite, talc or stable salts in powdered form. For this purpose I find that 55 I can deposit a film of carbon by smoking the plug with a gas flame. An alternative and somewhat preferable method from the standpoint of speed, reliability and simplicity of equipment required, is to coat the plug with a colloidal solu- 60

tion of finely divided material such as graphite. The coating may be accomplished with a brush, spray gun, or other suitable means. One method which I have found to be particularly suitable is 5 to use a tube slightly larger in inside diameter than plug 24 which is first dipped into the colloidal solution and then lowered over the tapered portion 26 of plug 24. A sufficient quantity of the colloidal solution is picked up by the 10 tube to deposit evenly a coating of the desired thickness. This thickness may be readily controlled by altering the concentration of the colloidal solution.

Having prepared the film which can be done 15 in production in a very short length of time, the wires 17 and 117, tubes 23 and 13 are placed in position. The machine used is essentially that which is well known in the art of stem making. In the successive operations of the machine the 20 glass is heated and pinched to form the press 14. In one of the final operations I prefer to apply air pressure to the exhaust tube 13 causing it to expand slightly at 22. This expansion of the tube greatly strengthens it at this point because 25 it rounds out any sharp junctions in the glass which might otherwise remain at the joint 20 where the exhaust tube 13 joins the press 14.

After passing through the annealing fires the completed stem is lifted from the wire block 27. 30 Due to the film 28 which I have previously applied to the plug 24 on tapered portion 26, the stem may be lifted without any sticking of the glass to the plug. Without this film I have found it practically impossible to remove the glass stem. 35 Upon removing the stem it is found that a portion of the film material has adhered to the glass on the inner wall of opening 16. I consider this to be no disadvantage inasmuch as it causes no undesirable effect in the use of the finished bulb. 40 If I use carbon for the film material, I find that that which adheres to the inner wall of opening 16 combines with oxygen in the subsequent annealing of the stem as is generally necessary in manufacturing any type of stem and consequently the carbon disappears. 45

For the plug 24, I have investigated the properties of various materials. I find that it is desirable to use a material of greater coefficient of thermal expansion than glass. A material such 50 as iron which was suggested by Burnette and Doane meets this requirement. However, for continuous use I find that a material which does not corrode so readily is desirable. For this reason I prefer to use brass or silver for the plug.

55 In manufacturing small tubes such as shown in Fig. 5, I make the press 14 directly on the end of the bulb 111. To obtain a shoulder against which to attach base 31, I roll a ring of glass 29 in bulb 111. The method for accomplishing this 60 is similar to that used in manufacturing homoeopathic vials and the like in which the glass is heated and a ring, bead or flange is rolled with a suitable tool. This process is well known and I do not claim any novelty in the method of making ring 29. The use of this method of mounting 65 a base to a bulb having an external press, i. e., a bulb in which the wires 19 and 119 are sealed with an exhaust tube 13 directly to the bulb I believe to come within the scope of my invention.

70 In making the external press in this type of bulb the procedure is similar to that described above. In Fig. 6 the plug 24 is positioned in wire die block 27 which is a part of a standard type stem making machine. Tapered portion 26 of

plug 24 is next coated with film 28 as described. An annular opening around the upper portion of the part of plug 24 which is within the wire die block 27 permits the insertion of exhaust tube 13. Wires 21 and 121 are placed in holes in wire die block 27 which are of proper depth to bring welded inserts 19 and 119 just above the wire die block. The extended portions 17 and 117 of the wires carrying filament 18 or other electrode assembly which may be of any desired construction, 10 are assembled before bulb 111 is placed in position above wire die block 27 in the stem machine.

In the operation of the stem making machine the glass below ring 29 is heated and pressed on to wires 19 and 119 and makes the seal with exhaust tube 13. After the glass is partially cooled, bulb 111 is removed from the machine without any sticking of the glass because of the action of film 28 on tapered portion 26 of plug 24.

It is understood that the nature and embodiment of the invention herein described and illustrated is merely a convenient and useful form of the invention and that many changes and modifications may be made herein without departing 20 from the spirit and scope of the invention.

What I claim as new and desire to secure by United States Letters Patent is:—

1. The method of making stems for electric lamps, vacuum tubes or similar devices requiring evacuation, which comprises coating a refractory 30 plug with a film of finely divided material, positioning a tube over said coated plug, positioning one or more wires parallel to said plug, positioning a hollow glass body over said tube, plug, and wires, applying heat and mechanical force to cause the fusion of a solid glass mass around the refractory plug, slightly expanding the internal and external diameters of said tube and then removing the assembly of said tube, wires and hollow glass body from said plug. 40

2. The method of making a bulb of the character described having an opening through the press for evacuation, which comprises placing on exhaust tube over a refractory plug, positioning a stem tube about said exhaust tube fusing said 45 tubes and uniting them under mechanical force to form the press about the plug, removing said mechanical force, applying fluid pressure to the interior of said exhaust tube and withdrawing said plug. 50

3. The method of making a bulb of the character described having an opening through the press for evacuation, which comprises forming the press with an exhaust tube attached about a plug of the like to mold an aperture through 55 the press into the exhaust tube, then producing a fluid pressure within said exhaust tube and subsequently removing said press from said plug.

4. The method of making stems for electric lamps, vacuum tubes or similar devices requiring 60 evacuation, which comprises coating a refractory plug with a film of finely divided material, positioning a tube over said coated plug, positioning one or more wires adjacent to said plug, positioning a hollow glass body over said tube, plug and 65 wires, heating the glass and wire to a temperature sufficiently high to fuse the wire to the glass, molding the glass about the wires and the plug, slightly expanding the internal and external diameter of said tube and then removing the assembly of said tube, wires and hollow glass body from said plug. 70
